CLAIM

We claim the ornamental design for a magnet grabber, as shown and described.

DESCRIPTION

FIG. 1 is a perspective view of our magnet grabber invention. FIG. 2 is a front elevation view of thereof.

FIG. 3 is a rear elevation view thereof.

FIG. 4 is a side elevation view thereof.

FIG. 5 is a side elevation view thereof.

FIG. 6 is a top plan view thereof; and,

FIG. 7 is a bottom plan view thereof.

The broken lines in the drawings illustrate features of the article to which the design is applied that form no part of the claim.
